UNITED STATES PATENT OFFICE

103,961

DESIGN FOR AN ASHTRAY

Donald C. Wharton, Pittsburgh, Pa., assignor to Kensington, Incorporated, New Kensington,
Pa., a corporation of Pennsylvania

Application January 21, 1937, Serial No. 67,195

Term of patent 3½ years

To all whom it may concern:

Be it known that I, Donald C. Wharton, a citizen of the United States, residing at Pittsburgh, in the county of Allegheny and State of Pennsylvania, have invented a new, original, and ornamental Design for an Ashtray, of which the following is a specification, reference being had to the accompanying drawing forming a part thereof.

Fig. 1 is a top plan view, and Fig. 2 is a view in elevation of an ashtray embodying my new design.

I claim:

The ornamental design for an ashtray as shown.

DONALD C. WHARTON.
